US0D1079529S

(12) **United States Design Patent** (10) Patent No.: **US D1,079,529 S**
(45) Date of Patent: ** Jun. 17, 2025

(54) **FINGER RING**

(71) Applicant: **Lilia Friedman**, Livadia (CY)

(72) Inventor: **Lilia Friedman**, Livadia (CY)

(**) Term: **15 Years**

(21) Appl. No.: **29/992,469**

(22) Filed: **Mar. 8, 2025**

(51) LOC (15) Cl. **11-01**

(52) U.S. Cl.

USPC **D11/26**

(58) **Field of Classification Search**

USPC D11/6, 26-27, 38-39, 89; 63/15.7

CPC A44C 5/00

(57) **CLAIM**

The ornamental design for a finger ring, as shown and described.

DESCRIPTION

FIG. 1 is a front perspective view of a finger ring, according to a first embodiment of the present invention;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a finger ring, according to a second embodiment of the present invention;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

1 Claim, 14 Drawing Sheets
